FRAME FOR A PICTURE OR SIMILAR ARTICLE

Isaac Mershon, Brooklyn, N. Y., assignor to Globe Silver Co., Inc., New York, N. Y., a corporation of New York

Application March 23, 1954, Serial No. 29,666

Term of patent 7 years

(Cl. D29—20)

To all whom it may concern:

Be it known that I, Isaac Mershon, a citizen of the United States and resident of the Borough of Brooklyn, county of Kings, city and State of New York, have invented a new, original, and ornamental Design for a Frame for a Picture or Similar Article, of which the following is a specification, reference being had to the accompanying drawing, forming a part hereof.

Fig. 1 is a front elevational view of a frame for a picture or similar article showing my new design; and

Fig. 2 is an end elevational view thereof, the

The dominant features of my design reside in the portions shown in full lines.

I claim:

The ornamental design for a frame for a picture or similar article, substantially as shown and described.
